Des. 191,456
Patented Oct. 3, 1961

191,456

WHIRLING TOY

Severino J. Cabanban, 10 W. 104th St., Apt. 3R,
New York, N.Y.

Filed June 19, 1959, Ser. No. 56,424

Term of patent 14 years

(Cl. D34—15)

FIGURE 1 is a perspective view of the whirling toy showing my new design.

FIGURE 2 is a side view taken on the line 2—2 of FIGURE 1.

FIGURE 3 is a top plan view shown with the cord wound up.

I claim:

The ornamental design for a whirling toy, as shown.
